UNITED STATES PATENT OFFICE.

CLINTON ALVORD, OF WORCESTER, MASSACHUSETTS.

COLOR-PRINTING MECHANISM.

1,383,253.

Specification of Letters Patent. Patented June 28, 1921.

Application filed August 20, 1919. Serial No. 318,716.

To all whom it may concern:

Be it known that I, CLINTON ALVORD, a citizen of the United States, residing at Worcester, in the county of Worcester and 5 States of Massachusetts, have invented a new and useful Color-Printing Mechanism, of which the following is a specification.

My invention relates to improvements in color-printing mechanism and more particularly to means for printing stripes of color upon warp yarns prior to the operation of weaving carpet or tapestry with manifold color designs.

The main and broad object of my invention is to provide an automatic color printing machine for applying color upon yarn used in the manufacture of carpets, plush, or pile goods for upholstery.

Another object of my invention is to stretch a number of threads side by side preferably upon a drum upon which they are wound so that they may each extend circumferentially around and together cover them transversely over the periphery of 25 the drum and may thus be striped by colors throughout their length, each color being applied separately and automatically, the positions upon the yarn where these stripes are to be applied being determined by jac- 30 quard mechanism.

A further object of my invention is to provide an automatic device for eliminating the color ridge between consecutive color stripes.

35 A further object of my invention is to provide a device wherein coloring matter is adapted to be applied preferably to a movable yarn carrier upon which yarn may be stretched in any desirable manner and 40 advanced in any desirable manner to a position to be operated upon by mechanism applying the coloring matter controlled by pattern controlled instrumentalities in accordance with a predetermined pattern de- 45 sign.

50 A good way of putting my new device into practice and a still further object of my invention is to provide selectively controlled mechanisms for moving a color car carrying a submerged revolving coloring pulley in such a manner that the car will pass from side to side of the yarn carrying drum and allow the pulley to print the yarn as the color car moves under the drum cross-wise,

the printing surface of the pulley normally 55 being as wide as the total length of one pile tuft. This movement of the color car is effected automatically and in such a manner that the drum moves only after the color car has moved beyond either side of the drum 60 and comes to a stop when the coloring pulley is to be applied against the yarn wound on the drum.

Another object of my invention is to automatically position the rotatable yarn 65 carrying drum for engagement by the coloring pulley by means of an index wheel responding to the requirements of a definite pattern through a jacquard or other pattern mechanism. This index wheel is adapted to effect, through certain instrumentalities expressly devised therefor, the movement of the movable yarn carrier, which may be a drum, or other suitable yarn support or holder etc. over varying distances 70 and during variable intervals, sometimes consecutive, and sometimes non-consecutive intervals. In effecting each move of the drum over a given distance to position it for engagement by the coloring pulley use 75 is made of an actuator for said index wheel adapted to operate in such a manner that, in enabling the drum to cover its greatest distance between two consecutive stripes of color this actuator may have to make plural 80 strokes. This condition developing, it has been found necessary to devise special 85 mechanism for automatically stopping the color-car and coloring pulley at an interval enduring as long as the drum is being 90 turned intermittently before reaching its color receiving position. Owing to the peculiar operation of this actuator it has also been found necessary to devise instrumentalities for preventing the premature 95 automatic operation of the scraper mechanism explained above whereby the scraper will obey the movements of the color-car and not those of the drum which, as already explained, may move independently of the 100 color-car.

With the above and other objects in view my invention consists in the combination, arrangement and details of construction disclosed in the drawings and specification and then more particularly pointed out in the appended claims. It is not to be construed that since I have shown my invention ap-

plied to a printing drum in this application, that I am limited to this style of yarn printing mechanism.

In the drawings wherein similar reference characters designate similar parts throughout the respective views,

Figure 1 is a front elevation of the yarn carrying cylinder showing my attachment applied thereto.

10 Fig. 2 is a side elevation of scraper actuating mechanism.

Fig. 3 is a fragmental side elevation of said drum, showing also the color-car and mechanism, in diagram, for operating same.

Fig. 36 is a side elevation of the color car control mechanism,

Fig. 37 is a plan view of Fig. 36.

55 In drawings which are merely illustrative of my invention 1 is the cylinder upon which the yarn is wound transversely of the periphery thereof in the usual way, and 2 is the track carrying and guiding the color-car 3 moving thereover with its V-grooved

60 wheels 4. The color-wheel 6 is rotated in the conventional manner, which is common to printing drums and revolves in the coloring matter contained in the color-box 5 which is loosely held in the color car 3, the pulley or wheel 6 picking up the color neces-

sary to lay a color stripe against the yarn wound on the drum. The top part of the color car 7 is hinged to the color car 3 at 8 Fig. 3 and is pushed upward by the spring 9 in the usual manner. The normal position of the color pulley 6 is such that the top thereof is slightly above the lowest part of the cylinder or drum 1, the color-wheel being adapted to be crowded down against the yielding resistance of spring 9. 75

The yarn which is to be laid on the cylinder preparatory to being colored is wound on the spools 16 held on spindle 17 and frictioned by pad 18 which is pressed up against the lower side of the yarn on the spool by 80 the weight 19. The yarn 20 then passes upward through the yarn guide 21 which is attached to the guide rack 22 and thence to the cylinder 1. The cylinder or drum may be revolved by the usual system of pulley a 85 and gearing 160, 161, 162 and 163 which also causes the yarn guide rack 22 to move slowly across the face of the cylinder to lay the yarn one layer deep thereon, the rack being driven from the worm 164 in mesh with gear 165 while the motion is transmitted through the gears 166 and 167 to the shaft 168, the outer end of which carries the pinion in mesh with the rack 22. One or more skeins of yarn are wound off from the spools 16 and 95 laid beside each other on the cylinder and each end of each skein is made fast so that each round of yarn is under substantially the same tension and the yarn is laid smoothly and snugly on the cylinder so as to present an 100 even surface for the passage of the color pulley while the surface of the supporting cylinder acts as a printing surface against which the pulley presses the yarn to insure a proper penetration and an equal applica- 105 tion of color to each thread.

With the hand operated machines in common use the cylinder is placed in its various annular positions by means of hand-wheel and gearing so that one operative is constantly engaged in turning the cylinder by the hand-wheel. In carrying out my invention I get rid of this mechanism by employing a jacquard and a perforated pattern, thus substituting mechanical expedients for 110 the personal equation, the holes in the pattern being punched according to the requirements of the design, which design determines corresponding positions for the cylinder, and color-car with its coloring-pulley. 115

When two stripes of the color are laid beside each other so as to blend, some of the rather thick coloring matter crowds out from under the coloring pulley and a ridge of this thick dye is left where the two stripes 120 meet each other. For years it was common practice to scrape this surface color into the yarn by a hand scraper and thus even it off; and of late years it has been customary to use a mechanical scraper which is attached 125 130

to the color-car and which scrapes after the color-pulley, a common form of which is shown in Fig. 3, there being two scrapers 23 and 24. The car is moving in the direction of the arrow α , and therefore the scraper 24 is down so as to pass under the yarn without touching it, while the scraper 23 is just rising to an up position because its roller 25 is just climbing up the incline 26 of the 10 scraper controlling bar 27. The scraper 24 is down because the roller 28 has swung backward around the hinge pin 29 which was caused by the forward movement of the color-car. The opposite stroke of the color-car will cause roller 25 to swing upward and let down scraper 23 whereas roller 28 of scraper 24 will be thrown into a straight line and thrust up 24 so as to scrape behind the color-pulley. The scraper-controlling bar 20 27 in the ordinary hand controlled printing drum is raised upward by the pressure of the operative's foot working on a foot treadle 128, but in my invention the pressure on the lever for raising the scraper bar 27 25 is automatic in its action as will be described later on in this specification.

I contemplate applying my invention in the form of an attachment to the conventional type of hand printing machines for 30 coloring yarn, wherein the color-car, coloring-pulley and treadle operated scraper mechanism, as well as yarn cylinder and winding mechanism are already to be found. The jacquard mechanism which I employ is 35 but one form of pattern mechanism which I contemplate using. The perforated strip 30 of the jacquard is wide enough so that there can be enough holes across the strip for each jacquard needle and in practice I prefer to use fifty. The action of the jacquard is simple and practically like similar devices and a hole in the strip means that the griffe 31 will push the corresponding hook 32 backward or toward the left.

40 I will first describe my automatic attachment for selectively positioning the yarn cylinder 1. The cylinder 1 is formed with an internal circumferential rack 59, (see Figs. 1 and 6) with which meshes the pinion 50 58 fast upon the shaft 57 upon which is also fixed the spiral 56 which meshes with the spiral gear 55 fast upon the long extended hub formed on the index-wheel 33, which index-wheel is mounted so as to turn freely 55 on the stationary guide plate M''. The index-wheel is formed with a circumferentially-extending series of pin receiving openings 34'' in which slide the jacquard pushed pins 34. The index-wheel 33 is formed 60 with a ratchet 11^a upon its outer circumference, there being one ratchet tooth for each pin receiving hole, said holes 34' being respectively arranged about midway two adjacent operative faces of the ratchet teeth (see Figs. 10 and 32). Adapted to engage

the ratchet teeth 11^a is the pawl 38 carried loosely by the pawl lever or arm 37 which is free to oscillate back and forth about the axis 10^a of the ratchet for slightly more than half a circle being mounted freely upon the 70 long extended hub of the index-wheel 33 and being limited in its motion forwardly directly by the dead stop 39, and in its back or return stroke indirectly by the dead stop 40. One tooth of the ratchet 11^a corresponds 75 to one tooth on the regular index 60 of the yarn cylinder.

The jacquard hooks 32' are slidably mounted at one end in the stationary guide plate M'' concentric with the openings 34' 80 and at their other ends pass so as to slide through the vertical needles 36, in the conventional manner. These jacquard hooks 32 are arranged in a concentric series within the guide M and provide a concentric series 85 of pushers adapted to register with the pins 34 sliding in the holes 34' of the index wheel 33. It will be noticed that all of the pins 34 which it is proposed to push out and project through the holes 34' of the index wheel 90 are pushed out by their corresponding jacquard hooks 32 at the same time. The hooks 32 push the pins 34 until the shoulders 34^a of the latter (see Fig. 11) contact one side of the index wheel 33, whereupon the pins 95 will remain in fixed position and it will then be necessary to return the hooks to normal position. In order to do this I provide a bar 31' attached to griffe 31 and moving with it. This bar 31' in its rearward motion contacts with the upturned ends 32'' of those hooks 32 which have already been moved and thus retracts them.

The jacquard works whenever the index-wheel 33 has made one complete revolution 105 and at each action of the jacquard the forty-eight pins carried by the index wheel are reset in accordance with the desired pattern.

It is to be noticed that one of the pins 110 slidable in one of the holes 34' of the concentric series of preferably forty-eight holes is a spring projectable pin 35, which pin is normally held projected in its hole by the spring 35'. When the spring pin 35 occupies the 115 annular position shown in Fig. 32 the center line of the lever 37 will coincide with an imaginary line indicated XX on the drawings, known as the zero line. Each slideable projected pin 34 moves with its index wheel 33 in a clockwise direction accompanying the 120 ratchet teeth 11^a which are acted upon by the pawl and moved thereby. Whenever a pin 34 approaches the XX line or zero point it is retracted by the stationary retracting cam 54 placed conveniently near the right 125 hand side of the pin wheel 33 (see Figs. 10 and 11). Therefore while the index-wheel 33 makes one complete revolution all the pins which had been moved outward by the action of the jacquard are retracted to this 130

normal position by the cam 54, and at the zero point, when index-wheel 33 has been moved its full distance the spring pin 35 will also be retracted and held back by the 5 same cam.

The wires 32 of the jacquard act on the pins 34, projectable through the index-wheel 33, whenever index-wheel 33 is moved so the spring pin 35 in the index-wheel is at 10 the point XX shown in Fig. 10, called the zero point. The actuating arm or pawl-lever 37, shown in Fig. 6 moves up to this zero point at the completion of its forward working stroke. At each complete turn of 15 the index-wheel the spring pin 35 brings the wheel to a stop opposite zero position. The various pins are pushed outward toward the left in all cases where the corresponding needles 36 enter holes in the pattern strip. 20

In order to prevent any retrograde movement on the part of the index-wheel I provide the brake drum 61 which is fast on the gear 55 fixed on the axis 10^a of the index-wheel and the brake band 62 passing around it causes sufficient frictional resistance so that the ratchet tooth does not run away from the point of the pawl 38 and consequently the yarn cylinder 1 is always brought 25 to rest at the correct annular spacing. 30

There is a pusher 41 freely mounted upon the long extended hub of the index-wheel 33 and arranged to move into contact with the pawl lever 37 to urge it forwardly to the 35 end of its stroke so as to rest on dead stop 39. The pusher 41 is formed with an offset 41^b (see Fig. 34) which immediately impacts with projection 41^a on the pawl lever 37 to drive the latter always in a clockwise direction, while the return of the pawl-lever 37 is accomplished by means of the weight 42 (Fig. 6) suspended on the strap 43, the opposite end of which is attached to the drum 44 which is fast to the pawl-lever 37. The 40 pusher 41 receives its oscillating motion from the gear 45 fast on the pusher 41 which meshes with and is moved by the toothed rack 46 which is pivoted on the crank stud 47 in crank-arm 48 fast on shaft 49. 45

50 The shaft 49 is rotated by an intermittent fast and slow movement through the sector gears 50 fast on the shaft 49 and sector gears 51 fast on the color car motion crank shaft 52. The sector gears are placed so as 55 to cause the pusher 41 and therefore the pawl-lever 37 to move backward about twice as fast as they move forward and thus the pawl 38 drives the ratchet 33 forward with a relatively slow motion while the 60 pusher 41 is retracted to the limit of its throw in about one-half the time in which the forward stroke is made. The shaft 49 rotates two to one with the shaft 52.

The pawl lever 37 has a prescribed movement in an arc of a circle and in making its

full rearward sweep the pawl-lever 37 is adapted to pass a prescribed arcuate series of projectable pins 34, the pins however, being projected in back of said lever so as to arrest its movement. The pins 34 are arranged in a circular series and the teeth of the ratchet 11^a are so spaced that the lever 37 will be checked by any of them provided such a pin 34 be in projected position and in the path of rearward movement of the 75 lever 37. The pawl 38 will then be in a position to drop freely into the corresponding ratchet tooth and upon its forward movement the pawl 38 will rotate the ratchet. It will be noticed that the lever 37 carries a 80 lug 53 (see Fig. 6) which is the part that contacts any projected pin 34 during the rearward movement of this lever 37. A tooth on the ratchet 11^a corresponds to one tooth on the regular index 60 of the cylinder. The transmission mechanism between the ratchet-wheel and the drum consists of the meshed spiral gears 55 and 56, the latter being on shaft 57 shown in Figs. 1, 5 and 32. The pinion 58 is also mounted on 90 the shaft 57 and meshes with the rack 59 on the usual index 60 of the cylinder or drum 1.

In the hand operated machines the yarn cylinder index contains a large number of 95 teeth for the yarn cylinder, whereas I have provided only forty eight ratchet teeth and projectable pins 34, in my auxiliary index 33, for the same purpose, which enables me to employ a small number of jacquard hooks. 100 By setting and resetting these projectable pins 34 of the index wheel after each successive revolution thereof I am able to position the yarn cylinder selectively in any one of its annular spacings. 105

It will be understood that the forward stroke of the index pawl 37 which moves the ratchet 11^a and index wheel 33 clockwise also moves, through the above described cylinder-operating mechanism the yarn cylinder 1, which action takes place while the color roller 6 of the color car 3 is out of contact therewith, and therefore it is necessary to synchronize and time the action of the color car with respect to the yarn printing drum. 110

A continuously rotating shaft 52 is provided and is adapted to control the movements of the color-car and the scraper mechanism. I will first describe the means, 115 controlled by shaft 52, for operating the color-car, and will describe the use of the cut-out for said color-car operating means. As shown in Fig. 8 a hub 81 is splined fast on shaft 52 so as to rotate therewith. 120 Adapted to turn about and upon hub 81 is the hub 75 carrying the crank arm 75. The shaft 52 receives its motion from pulley a shown in Fig. 1 through the pinion gear 78 meshed with gear 79 which is fast on shaft 130

52. The hub 81 is formed at diametrically opposite points with the recesses 81' Fig. 8 which are dish-shaped in configuration. A locking bolt 80 is trunnioned partially in the hub 81 and partially in the hub 75' as shown in Fig. 8 and it operates in a manner similar to the well known power punch press control. The bolt 80 is cut away as at 80' where it extends into the hub 81 that is fast on shaft 52. The locking bolt 80 is adapted to be rotated in its seat in the hub 75' and into the recess bored in the hub 81 as shown in Fig. 8. The gear 83 is fast on the locking bolt 80 and serves to oscillate the locking bolt, this gear meshing with the gear 84 which is pivoted on the stud 85, mounted in one of two diametrically opposed lugs 70' formed upon the crank hub 75'. An abutting arm 86 terminating in a pawl 86' is pivoted on stud 85, and another similar abutting arm is pivoted on the stud 85' diametrically opposite the one on stud 85. The gear 84 has a crank arm 84' which is pivotally connected by a connecting rod 90' to the abutting arm mounted on the stud 85'. The spring 87 is secured at one point to the crank hub 75' and also to the connecting rod 90' as shown in Fig. 8. The spring normally holds the two abutting arms in the positions indicated in the form of the broken line pawls 86' in Fig. 8, this position of one of the abutting arms being shown in Fig. 12, whereupon it will be noticed that the locking bolt 80 has been rotated in its seat and into the recess bored in the hub 81 as shown in Fig. 12, and in that position it causes crank arm 75 to rotate in unison with the shaft 52. A revolving crank stud 10 Fig. 9 connects this crank arm 75 with a stroking arm 9' carrying a rack 11 at its lower end, this rack meshing with a sector gear 12 Fig. 3 which in turn meshes with the pinion 13 secured to a cord pulley 14 which moves the cord 15 back and forth so that the ends of the cords, being attached to the color-car in the usual manner will impart motion to the color-car whereby it will be stroked back and forth. It will be noticed that the rocking arm 8' fulcrums on the axis 7' of the sector gear 12 so as to carry the rack into engagement with the sector gear.

The jacquard sets up or registers the pins in the index wheel according to the design and the pawl moves the index wheel accordingly as its lever impacts in its rearward motion against the various protruding pins, the particular pin projected at any particular time determining the distance over which the yarn carrying cylinder moves at any period of rotation. The particular design may not call for making consecutive color stripes upon the yarn and it may be necessary to apply color stripes at various spaced apart intervals upon the yarn, hence the drum will sometimes move over greater distances than at other times. The index wheel provided has fewer pins than there are teeth around the circumference of the cylinder, so it may be necessary to turn the index wheel one or more times to register the intervals apart between which color stripes are to be applied to the yarn on the drum. In other words the cylinder may have to make several moves before it comes to rest to receive a color stripe. In this event it will be necessary to prevent the premature operation of the color applying mechanism furnished by the color car. Reference to Figs. 16 and 17 will show diagrammatically that the cylinder 1 turns while the pawl-lever 37 is moving clockwise as indicated by the arrow and stops while this lever is moving counter-clockwise or making its return movement; it will also be seen that while the cylinder is moved, and the sector gears 50 and 51 are causing the pawl 38 to move forward, the color-car has moved out from under the cylinder and is not in contact therewith. The range of movement of the pawl 38 covers twenty-four ratchet teeth or practically one-half of the total number of teeth on the index wheel; therefore any pin 34 projected opposite any of these 24 teeth assures that pawl 38 will turn the ratchet wheel and consequently the drum a similar number of teeth. As this takes place the color car is running back and forth on its track applying a color stroke to the yarn whenever the drum has ceased to rotate. The color car will apply a color stripe during each of its forward and backward strokes as illustrated in Figs. 17 and 20. So far the mechanism described is adapted to enable the cylinder to move over distances representing intervals up to 24 teeth or one-half of the index wheel. It may, however, be necessary to move the drum or cylinder over a greater distance. This being beyond the power of the pawl lever 37 to accomplish by a single stroke it will be necessary for it to make a double or duplicate stroke, the drum during this event, making two corresponding moves and therefore stopping twice, as it stops during each back stroke of the pawl lever 37. However, as the color-car strokes the yarn on the drum every time the drum stops it will be necessary to cut out its operation during the first stop of the drum and immediately reactivate it when the drum makes its second stop after having moved over the required distance, because the requirements of the carpet design has called for this larger skip of the index wheel.

The mechanism required to stop the movement of the color car must operate in such a manner that the color-car will be stopped in a position representing either extreme of its movement where it will be out of contact with the drum. It is necessary to cause

some impediment or check to operate to arrest the movement of crank arm 75 through the abutting arm 86. To effect this result there is provided a bell crank lever 63, Fig. 5, fulcrumed on stud 65 and having one arm held slightly above the dead stop 40 by means of the spring 40' and in position to be engaged by the lever 37, while its other arm 63' is pivotally connected to the connecting rod 66, the other end of which is connected to the lever 67 fulcrumed at 68 and provided with a cam end or portion 69 shown in Fig. 14, this cam end adapted to bear against a cam 69' 10 on the arm 70 of the lever 71 fulcrumed intermediate its ends upon the pin 110, the lever 71 carrying a segmental member 109 adapted to be contacted by the curved end 108 of a lever 105 pivoted on the pawl lever 15 37 at 106. The lever 105 is a bell-crank lever and the arm 104 thereof carries the roller 103 adapted to project into a notch 102 on the index wheel in line with the spring pin 35, this notch being cut directly into the 20 circular rim or ring 101 fast on the ratchet pin wheel 33, the spring 107 being adapted to retract the roller 103 into the notch 102 when the pawl lever 37 is arrested during its rearward stroke by the spring pin 35. I 25 have provided a 48th jacquard impelled pin, isolated from the pin 34 and have placed it directly in the center of recess 102 so when the pin 111 is in its projected position, it 30 will block up the recess 102 and prevent the entrance of the spring impelled roller 103 thereinto. The lever arm 70 carries at its end a connector 72 which is shown in Figs. 2 and 7, and this connector 72 is attached loosely to the tail 73 of the hook member 74 fulcrumed upon the pin 74' carried by the arm 35 93 of a bell-crank lever 91 fulcrumed upon the stud 92. The bell-crank lever 91 carries the roller 90' at its upper end, the roller being acted upon by either lobe or nose of cam 90 fast upon the continuously rotating shaft 52, as shown in Fig. 4, a spring 100 acting to normally position the lever 91 vertically when not acted upon by the cam 90. The hook member 74 carries the oppositely 40 extending hooks 90^a and 90^b at its upper end adapted to engage either with the dead stop lever 88 or with the lever 98. The lever 88 has a slot 89' the purpose of which is to hold a soft backing for the pin 89 serving as a 45 fulcrum for lever 88.

The end *c* of lever 88 is wedge-shaped and is adapted to be engaged by the stop 94' Figs. 4 and 36 formed upon the trigger 94, the stop 94' being normally held in engagement with the cam edge *c* of lever 88 so as to prevent this end of lever 88 rising higher, the stop 94' being urged against cam *c* by the spring 96 secured fixedly at D. The trigger 94 is suitably fulcrumed at stud 95. 50 The lever 98 is fulcrumed at E to lever 88

and has a cam head 98' inclined similarly to the inclined edge F of stop 94'. The lever 98 is normally held by spring 99 in the position clearly shown in Fig. 4 where the cam edge of the lever 98 is held out of engagement with the trigger 94.

It will be seen that a friction clamp 100 Fig. 8 is provided for the purpose of applying frictional resistance to the movement of the crank arm 75, this clamp being provided with opposing arms 82 and 82' bearing against the hub 75' of crank arm 75, in the well known manner of ordinary punch presses.

I will now describe the scraper operating mechanism. The foot treadle 128 Figs. 1, 2 and 35 is of the conventional type used in yarn printing machines and is fulcrumed at 134 being held in the position shown in Fig. 2 by the spring 130. The treadle, 35 as shown in Fig. 1 has connected to its arm 135 a link 136 which is connected to the scraper controlling bar 27. As the foot actuated scraper is a well known device, the drawings are therefore quite conventional 40 in showing this portion of the scraper mechanism, the purpose of the drawings being rather to show the new selective actuation of the already well known foot treadle type in which the motion from a depression of the treadle is transmitted from the treadle arm 135^a through the vertical link which is pivotally attached at its lower end to the arm and at its upper end to the scraper bar 27. The high position of bar 27 will cause the 45 scrapers 23 and 24, Fig. 3, to scrape in turn behind the color roll 6 while the low position of the bar 27 will cause these scrapers to drop so low as to miss entirely the yarn on the cylinder. It is designed that the position 50 of the pawl lever 37 controls the position of the scraper bar 27 and consequently the operation of the scrapers which are to function only when two stripes of the same color come together. For this purpose a bell-crank lever 115 Figs. 6 and 32 is fulcrumed at 116 and has a curved upper end 114 adapted to be engaged by the cam end 113 of the stroking pawl lever 37. The spring 110 132 normally positions the level 115 in such a manner that arm 115 thereof will be arranged vertically. The flexible connector 117 has one end attached to the lever 115 and has its other end attached to the weighted end 119 of a pawl 120 which is pivoted on 115 stud 121 as shown in Fig. 35; the stud 121 being secured to a part G fixed on the connecting rod 127 which is connected to the foot treadle by means of the pin 129. The flexible connector 117 at points between its 120 ends is trained over the sheaves 117^a and 117^b, also shown in Fig. 35. The pawl 120, it will be seen, is disposed at an angle relatively to the weighted arm 119. Slidably mounted on connecting rod 127 as by means 125

of the lugs G' is a slide 123 carrying a roller 125 being acted on by the cam 122 also fast on the continuously rotating shaft 52. The slide is held in the position shown in Fig. 2 by means of the spring 124.

I provide mechanism serving as an auxiliary control for the scraper mechanism as follows. I have elongated the rearward part of the dead stop 88 Figs. 4 and 35 and pivoted a pawl 138 thereon at 139. The upper end of pawl 138 is adapted to engage with one of three teeth 140 spaced circumferentially upon a ratchet 141 which is fast on the shaft 142 which is free to turn in bearings not shown. Also fixed upon the shaft 142 is a cam 143 which is formed with depressions M for the reception of a roller 144 carried by the arm 146 of lever 147 which is fulcrumed at 148. The free end 149 of the lever arm 147 is attached to weighted end 119 of pawl 120 by the flexible connector 150. Another three toothed ratchet 157 is fast on the shaft 142 and the arrangement of this ratchet is such that one tooth 25 of the other ratchet 141 will be disposed normally, in the position of the parts shown in Fig. 4, between two teeth of the ratchet 157. Resting between two teeth of ratchet 157 is a pawl 156 Figs. 2, 4 and 35 fulcrumed at 155 and carried by the vertically arranged lever 152 which is fulcrumed upon a pivot 153 and has a roller 151' adapted to be acted upon by either of the two lobes of cam 151 also fast upon the shaft 52. The spring 154 is arranged to normally hold the arm 152 in a vertical position not shown in Fig. 4.

The mode of operation of my invention will now be explained. It must be remembered that one revolution of the constantly revolving shaft 52 will normally cause the color-car to make two passes under the yarn cylinder 1 and also that similarly the cam 122 will always depress scraper-slide 123 twice for each revolution of shaft 52 and hold it down while the color-car is thus passing under the cylinder. However the scrapers will not be thrown into action unless weighted pawl 120 is allowed to swing into operative position where lug G' can contact with its tip, or working end, and thus cause the connector 127 and treadle 128 to be depressed by the downward motion of slide 123 and thereby raise the scraper bar 27, which act will always cause the scraper 23 or 24 to scrape in turn behind the color-roll 6. The scraper-bar 27 must be held up in a stationary position while the color-car is passing under the yarn cylinder, and at this time the cylinder is at rest, and the index-pawl-lever 37 is making its rearward or inoperative stroke.

The yarn cylinder is moved by the urge of pawl 38 on lever 37, and during such rotation of the yarn cylinder the color-car is 65 out from under it as shown in Fig. 3, and

during this period of time, when the color-roll is not in contact with the surface of the yarn cylinder, the scraper slide 123 is retracted by the spring 124 and then again forced downward by the constant rotation 70 of cam 122, and it arrives at its lowest position just as the color-car again reaches the edge of the yarn cylinder on its next stroke. The scraper slide 123 always moves downward at each forward stroke of index-pawl-lever 37 even if the scrapers 23 and 24 are not to operate, or even if the color-car is cut out of action because of a large skip of the yarn cylinder 1.

The action of the cylinder, color-car and 80 scraper will now be clearly explained and the explanation will come under six conditions or heads as follows:—

First when the index-pawl 38 is making skips of two teeth or more but not over 85 twenty-four teeth; second the stopping of the color-car whenever the spring-pin 35 arrests the index-pawl-lever 37 and the pattern to be printed does not call for a color stroke at the spring pin stop; third the manner of 90 making a color stroke at the spring-pin position whenever the requirements of the pattern demand it; fourth the action of the mechanism when large skips of over twenty-four teeth are made; fifth the action of the 95 scraper which must operate only on the second of two consecutive color stripes of the same color *i. e.* only while blending stripes of the same color are being laid; and sixth automatic stoppage of the scraper, or 100 the action of the scraper cut-out, whenever the index-pawl after stopping at the spring-pin is pushed to the zero position, when the pattern does not require a color stroke but when the next rearward pin 34 upon the next 105 set up is pushed out by the jacquard for a color stroke.

I will now describe the first condition:— The index-pawl lever 37 is moving backward for skips of from two to twenty-four teeth, 110 and when arrested in its rearward motion by a jacquard protruded pin 34, while being retracted by weight 42, it will on its working stroke revolve the index wheel 33 up to the zero position by a skip equal to the pins 115 passed over during its retraction. The friction strap 62 will exert sufficient drag to cause the ratchet 38 to come to rest at the zero position; and the yarn cylinder will revolve in unison with the ratchet and come 120 to rest, being likewise checked and held by the friction. The rotation of the shaft 52 will cause the crank-arm 75 to revolve because dead-stop 88 is as shown in Fig. 12 and thus the color car will stroke backward 125 and forward under the cylinder, and the parts are so timed and designed that the color-car will contact with the cylinder only while the cylinder is at rest, and the cylinder will turn, under the forward urge of the 130

pawl, only while the car is passing beyond the edge of the cylinder coming to rest and returning again to contact once more with it.

This action will continue until the index-pawl-lever 37 is checked rearwardly, as it always must be, by spring pin 35 and I will now explain the second condition which is the cut-out of the color-car action when the pawl lever is stopped by the spring-pin.

10 As soon as index-pawl-lever 37 checks at the spring-pin 35 on a short skip the roller 103 Figs. 7 and 33 on lever 105 will drop into the recess 102 of the circular rim 101, being urged there by spring 107 and the end 108 of this lever will contact somewhere on the curved end 109 of lever 71 (see Figs. 10 and 33) and move it so that the motion of the roller 103 into the recess 102 will be transmitted through the connector 72 to the hook member 74 and the head 90^a will be thrown over against the dead-stop 88, see Fig. 2. The rotation of cam 90 on shaft 52 always causes lever 91 to make a working stroke and now forces lever 93 down carrying with it hook 90^a of member 74 which, being up against lever 88 will hook onto it and likewise draw down the pawl end 88' of this dead-stop lever 88 far enough to allow latch 94 to move forward under the action of its spring 96 and catch on to and hold lever 88 in a horizontal position as shown in Fig. 4. Thus the end 88' will be raised into the path of movement of one of the abutting arms 86 carried by the crank-arm 75 and upon contact thereof the locking bolt 80 will be revolved and the crank-arm freed from the hub 81 of the revolving shaft 52 and the crank arm 75 will come to rest on one of its dead centers, and consequently the color-car which is moved thereby will halt at one of its extreme positions away from the yarn cylinder.

The jacquard will now again indicate and re-set the pins 34 in the index wheel 33 for the next revolution of the index wheel and the pawl-lever 37 will again be retracted by the weight 42 until it comes into contact with the next jacquard protruded pin 34.

This rearward stroke of the pawl-lever 37 away from the zero position, and the spring pin 35 will cause the roller 103 to be cammed by the edge of the recess 102 and the consequent motion of lever 105 will be transmitted through lever 71 and connector 72 to member 74 and hook 90^b thereof will be moved away from dead-stop lever 88 by retraction of spring 74" and against trigger-lever 98 (see Fig. 37). The hook will have raised under the action of spring 100 which pulls lever 93 upward as the lobe of cam 90 passes out from under roller 90', and the parts will be positioned as shown in Fig. 15 with hook 90^b already to catch onto trigger lever 98 and pull it downward when the hook is depressed again under the influence of the down

stroke of lever 93 and thus force the retaining catch 94 off cam edge C of dead-stop 88 as shown in Fig. 36 and allow it to move upward, under the action of spring 100. Fig. 36 shows the dead stop 88 as free from its retaining catch 94' and just ready to move under action of the spring 100 out of engagement with abutting arm 86. This action will move the end 88' down away from the abutting arm 86 and allow the locking bolt 80 to re-engage crank-arm 75 with the revolving hub 81 and shaft 52 and the color-car will begin to stroke again and will continue to do so until the pawl-lever 37 again contacts against spring-pin 35 as it must always do. The above action will then be repeated unless the third condition is fulfilled which is that the pattern calls for a color-stroke when the spring-pin reaches the zero position.

The third condition exists when the isolated index-pin 111 is projected by the jacquard so as to cause the color-car to stroke at the spring-pin according to the design, and as this pin 111 is located in the mouth of recess 102 of the circular rim 101 the roller 103 cannot enter the recess and therefore the action of cutting-out the motion of the color car as described under the second condition cannot take place. Consequently the car will continue to stroke until the index-pawl lever is once more checked by the spring-pin, and if the pattern does not call for a color-stroke at that particular member then the color-car will stop as described under the second condition. Thus far all the strokes of the index-pawl have been for skips but none of them have been for more than twenty-four teeth, and I will now describe the manner of making larger skips which comes under the fourth head.

When the design calls for a skip of more than twenty-four teeth between any two stripes of the same color, it will be necessary to bring the color-car to rest while the drum is turning the requisite number of teeth.

A specific example will make the mode of operation clearer. Let us assume that the sixth index-pin is at the XX position and that the color-car is laying a stripe on the yarn. The next stripe of that color, as shown by the design, is not to be laid on until the drum has turned 83 teeth, which obviously necessitates stopping the motion of the color-car. While the color-car is passing under the cylinder the pawl-lever 38 will be moving rearwardly and, as no pins have been projected by the jacquard the pawl will be retracted twenty-four teeth by the weight 42 until it contacts the head 64 of lever 63 at which time the pawl 38 will drop into the tooth corresponding to the thirtieth pin which is twenty-four back of XX. One arm 64 of the bell-crank lever 63 when contacted by the pawl-lever will move against dead

stop 40 (see Fig. 32) against the tension of spring 40', thus arresting the pawl-lever's rearward movement while the other arm 63' of lever 63 will pull connector 66 to which it is pivotally connected (see Fig. 6) thus forcing the cam-end 69 of lever 67 against the cam 69' on arm 70 of lever 71 which lever transmits the motion through connector 72 and throws 90° against dead-stop lever 88 so that its next regular depression caused by cam 90 will draw down end 88'' and likewise elevate end 88' which will operate locking bolt 80 as described under condition two above, for the cut-out of the color-car motion, and consequently the color-car will stop.

The pawl-lever will next move forwardly carrying the thirtieth index-pin to the XX position but, of course, the yarn will not be striped as the color-car has been stopped. The pawl-lever 37 will then be retracted again until it contacts spring-pin 35 at which time the roller 103 will be forced into the opening 102 and the same condition exists as already described under the second condition for, although the hook 90^a again moves downward nothing is changed. Since the spring pin is only eighteen teeth back of the tooth previously engaged by the pawl the total number of teeth skipped has been twenty-four plus eighteen or forty-two. The example stated that there is to be a skip of eighty-three teeth which therefore means that the pawl-lever must fall back forty-one more teeth before it can strike a jacquard projected pin.

As already described under condition two the jacquard will reset the index-pins whenever spring pin 35 comes to XX position and it is evident from the example that the forty-second pin will be the first, numerically, to be projected. The pawl-lever will then be retracted again and since none of the first twenty-four pins have been projected it will contact again against lever 63 as previously described under this condition, thus keeping the color-car still at rest. The twenty-fourth pin will be carried to the XX position after which the pawl-lever will be retracted until it contacts the first projected pin which is the forty-second. The color-car will be started in motion exactly as described under condition two when contacted against a projected index-pin and the forty-second pin will be brought to the XX position just before the color-car reaches the cylinder and then the desired color impression will be made upon the yarn on the cylinder.

The fifth condition is the scraper motion which is thrown into action immediately after the color-roll begins to make the second of any two consecutive strokes of the same color. The index-pawl being checked rearwardly for a skip of less than twenty-four teeth by a jacquard protruded pin then makes a working stroke up to the zero point

thus positioning the yarn cylinder and the color-car makes its necessary stroke.

Every time the index-pawl lever 37 moves up to the zero point, as mentioned in any of the above descriptions, it comes in contact with the end 114 of lever 115, see Fig. 6, and moves the horizontal arm 118 downward against the action of spring 132 and therefore slackens up on flexible connector 117 which allows the weighted arm 119 of 75 scraper pawl 120 to drop and allows the working end of the pawl 120 to swing toward the left where it will be in working position to be contacted by lug G' of slide 123. However it cannot swing in under lug G' on a skip tooth movement of index-pawl because lug G' has already been forced down beyond the working point of the pawl 120, for, as already described the scraper slide 123 must be all the way down as soon as the color-roll 85 in the color-car contacts with the yarn cylinder, and this takes place as soon as the index-pawl lever reaches XX at which point the cylinder always comes to rest. Hence the scraper bar 27 will not be thrown up on any 90 skip tooth movement of the index pawl. If the next rearward movement of the index-pawl is for one tooth only, when, in other words, the consecutive rearward pin has been projected by the jacquard, then the extended 95 end 113 of pawl lever 37 will not move back far enough to become disengaged from end 114 of arm 115 and thus the arm 118 is still kept in its lowered position and the flexible connector 117 is still under slack and the 100 weighted end 119 of scraper-pawl 120 is consequently likewise still down, then during the next downward move of the scraper the slide 123 will cause lug G' to contact against the working end of scraper-pawl 120 105 and the depression of the connector 127 and therefore of the treadle 28 and the elevation of the scraper bar 27 will take place and one of the scrapers, either 23 or 24, will be ready to fulfil its function and scrape during the 110 coming stroke of the color-car against the yarn stretched on the cylinder, because cam 122 will hold slide 123 down until the color-car finishes the stripe. The device will continue to be thrown in and scrape so long as 115 one protruding index-pin follows its predecessor; and as soon as the index-pawl lever 37 moves backward two or more teeth, or a skip, then the end 114 of lever 115 will no longer contact with extended end 113 of the 120 pawl lever, and consequently spring 132 will raise the arm 118 and therefore the weighted end 119 of scraper pawl 120 through the flexible connector 117 and the working end of the pawl will be missed by lug G' of 125 scraper slide 123 on its next downward stroke, and consequently no action of the scraper will take place.

I will now describe the sixth condition, or the scraper cut-out. As has been previously 130

explained the scraper will be set to scrape, *i. e.*, the weighted pawl 120 will swing into operative position, whenever the pawl lever falls back one tooth from the XX position, 5 but it is evident that, if one set-up of the pins by the jacquard does not call for a color stripe at the spring-pin 35 then the color-car mechanism will not operate; and if the next jacquard set-up does call for a stripe at 10 the first pin back of spring pin then the scraper would be set to scrape on a stripe which was not immediately adjacent to one of the same color.

As already described under the second 15 condition, when there is to be no color stroke at the spring-pin the end 88' of lever 88 is raised to stop the color-car, and consequently pawl 138 secured to this lever has been lowered. The pawl 138 fulcrumed at 20 the end of this lever 88 at 139 will be raised again whenever the end 88'' of lever 88 is raised, and incidentally the end 88' drops away from the abutting members 86, thus causing pawl 138 to turn tooth 140 of ratchet 25 141 and therefore also cam 143. The roll 144 of lever 146 is forced down by the lobe of the cam 143 thus raising the other arm 149 of the lever 146 and hence pulling up the weighted end 119 of pawl 120 through 30 flexible connector 150 and preventing a scraper treadle depression when the first pin is at the XX position. This is the scraper cut out, but now it must be rendered inoperative as it is possible that the next pin 35 might call for a stripe and in that case the scraper must operate. Pawl lever 152 is being constantly reciprocated by cam 151 but pawl 156 normally cannot turn ratchet 157 as its motion carries it back and forth be- 40 tween two teeth. However when the ratchet has been turned one sixth a revolution as just described, the pawl 156 on its next working stroke, acting on ratchet 157 the tooth of which it can now reach, will turn 45 the cam 143 again one sixth of a revolution so that the roller 144 of lever 146 will drop into the recess of the cam and consequently the flexible connector will be lowered and rendered slack so that the scraper-pawl 120 50 is again free to be acted upon by its regular flexible connection 117 which is at- tached to arm 118 of lever 115 and which works through contact with end 113 of in- dex pawl lever 37 just as described under 55 the fifth condition explained above.

The same condition will exist when making a twenty-four tooth skip when no pin has been projected by the jacquard, the only difference being that the color-car cut-out 60 is operated from the movement of lever 63 which shifts the dead stop lever 88 and thus stops the color-car mechanism, which lowers pawl 138 so it will, on the next movement of lever 88, be raised and thus make the 65 first one-sixth of a turn of the scraper cut- out cam. This turning of the scraper cut-out cam will cause pawl 120 to assume its inoperative position. The cam will be turned the second necessary one sixth of a revolution by the action of pawl 156, just 70 as already described above, and the scraper cut-out will be brought back to normal again where it leaves pawl 120 in a position to be controlled by lever 115. This scraper cut-out will always operate whenever the 75 color-car crank arm 75 is started up, be- cause the depression of the end 88' of the dead-stop lever 88, which allows the lock- ing bolt to turn and drive the crank arm 75, will cause the elevation of the pawl 138 80 and compel the turning of the scraper cut-out cam. In all such cases the very next stroke of pawl 156 will give the scraper cut-out cam the necessary impulse and it will be brought back to normal where it will re- 85 main until the color-car motion is once more stopped and then restarted.

The requirements of coloring yarn for any 90 design will probably call for all six of these above described conditions, and of course they can come in any order, and be repeated any number of times.

The mode of operation of my invention 95 will now be graphically described and I will explain the same six conditions of op- eration of cylinder, color-car and scraper from Fig. 15 to 28 inclusive, which are dia- grammatic. The description will however follow a somewhat different order, for the requirements of the design could call for 100 any order of sequence.

Figs. 15, 16, and 17 show the position of the members for condition one with the index pawl making skips of less than twenty- 105 four teeth. Dead-stop 88' is down or in inoperative position and therefore crank- arm 75 is revolving and consequently the color-car is stroking under the cylinder. In Fig. 15 the pawl-lever 37 has just reached and been arrested in its rearward stroke by 110 a jacquard protruded pin 34; the pawl 138 is up and standing still, while horizontal pawl 156 has reached its extreme right- hand or working stroke, which in this case is an idle one, and which will always be an 115 idle one unless pawl 138 has first moved down into working position and then up again and given its ratchet a turn of one- sixth of a revolution, because pawl 156 can- not reach the next tooth and then turn its 120 three toothed ratchet until the upward thrust of pawl 138 has just moved the shaft 142 and thus moved a tooth of ratchet 157 forward into reach of pawl 156. Scraper slide 123 which has not this time operated 125 the scraper is just starting upward and the color-car with both scrapers in an inopera- tive position is leaving the cylinder 1 and moving in the direction of its arrow. Yarn cylinder, or drum, 1 is nearing the end of 130

its stop or period of rest and will be moved forward upon the working stroke of index pawl lever 37, driven by the advancing pusher, which is shown in Fig. 17 as at the extreme of its working stroke at the XX or zero position. In Fig. 16 the advancing pusher has just contacted with the index-pawl-lever and will push it over to the zero position and therefore causing the 10 yarn cylinder to turn to its new position. The color-car has reached its extreme right hand movement and is about to begin its opposite stroke because the color crank arm is on dead center. The member 74 with its 15 hooks 90^a and 90^b started down just as the pusher began its working stroke and is shown in its down position but this working stroke did not change anything except pull down trigger 98 which it will always 20 do unless the hook 90^a is forced over against dead-stop 88. Scraper slide 123 is up.

Fig. 17 shows the color-crank-arm as advanced one sixth of a revolution which has advanced the car up to the cylinder just as 25 it has come to rest with the index-pawl at XX. Hook member 74 has raised under action of its cam 90 and horizontal pawl 156 is now in the middle of its working stroke which will never turn its three toothed 30 ratchet 157 until the long pawl 138 has first turned its three toothed ratchet 140 one sixth of a revolution. The index pawl has contacted with lever 115 and depressed arm 118 so as to slacken up on the flexible connector 35 and thus allow weighted arm 119 of pawl 120 to drop and thus swing the working end of the pawl into operating position, but the scraper slide descended just before this and therefore the lug G' passed pawl 120 and 40 the scraper treadle 128 was not depressed.

Fig. 18 shows the beginning of the fifth condition or the action of the color-car cut-out. The color crank is two-thirds up and the car, with its rearward scraper depressed, 45 just passing out from under the yarn cylinder; pawl 156 has finished its idle working stroke, the scraper slide is on the point of rising and the index pawl pusher has moved back to its extreme left hand position, and the pawl-lever has been retracted rearwardly one space, and has been arrested by a jacquard protruded pin.

Fig. 19 shows the color-crank on its top dead-center with the car at the extreme left hand. Member 74 is down and has idly brought down latch 98, the scraper slide is up, and trigger lever 115 is still in contact with the end of pawl-lever and therefore pawl 120 is in operative position and the 55 pusher is mid-way in its operative stroke and has not as yet contacted with the pawl-lever and consequently the cylinder is still at rest. Fig. 20 shows crank moved forward one-sixth of a revolution with the car just 60 contacting the cylinder, index-pawl is at XX with consequent stoppage of the cylinder after having moved forward one tooth, the scraper slide has moved down and lug G' has contacted with the working end of pawl 120 and therefore carried it down and therefore treadle 128 has been depressed while scraper bar 27 has been raised, consequently the rear scraper, or the one following the color-roll, has been forced up into operative 70 position and will scrape the yarn behind the color-roll because this is the second stripe in succession of the same color. Fig. 17 shows the beginning of one stripe and Fig. 20 the beginning of the next one and the cylinder has moved only one tooth. Fig. 21 80 illustrates the beginning of a full skip of twenty-four teeth without a protruding index at the twenty-fourth tooth which is to be followed by a rearward retraction of the index pawl of one tooth only and therefore Figs. 21 to 26 inclusive will show both 85 condition four, where a large skip is made of over twenty-four teeth, in this particular case twenty-five teeth, and also shows the 90 scraper cut-out or the sixth condition.

Fig. 21 shows the color crank arm 75 approaching the bottom dead center and therefore the car is passing out from under the cylinder, index-pawl is at its extreme rearward location, and has impacted against 95 head 64 of lever 63, see Fig. 7, and through the various connectors has swung hook number 74 over against dead-stop lever 88.

The view of hook member 74 in all these diagrams is turned through an angle of 100 ninety degrees so as to show the hooks on the head, and is represented as being swung to the left or right, while in practice it is 105 really swung in a plane perpendicular to the plane of the paper; as the figures are wholly diagrammatic and for illustration only the position of the member 74 is thus shown for clearness of perception.

When the hook is toward the left in these 110 diagrams it is supposed to be contacting with lever 88 and when over toward the right it is in contact with latch 98. Hook member 74 in Fig. 21 is just beginning to be depressed by the influence of its cam 90; trigger lever 115 is no longer in contact with 115 the end of the index pawl lever and therefore the end 118 has swung up somewhat under the retraction of its spring 132 and has tightened the flexible connector 117 but the hooking action of lug G' and pawl 120 is such that while under working strain the 120 spring 132 is not sufficiently strong to pull the end of pawl 120 away from the grip of lug G' and hence flexible connector is shown as taut. Fig. 22 shows how the continued 125 downward motion of hook member 74 has pulled dead-stop lever 88 horizontally where it is held by spring catch 94 and where the working end 88' is in the path of the abutting arms 86 and the continued rotation of 130

crank arm 75 has caused one of the abutting arms to contact with end 88' and cause locking bolt 80 to revolve until the bolt turns out of its seat 81' in hub 81 which is fast on 5 continuous revolving shaft 52 and hence crank-arm 75 being now free from shaft 52 has come to rest on dead center, which stoppage has brought the color-car to rest at its extreme position. The movement of 10 lever 88 brought pawl 138 down so it got under a tooth of its ratchet 141. The pusher is urging the pawl-lever, and consequently the ratchet and cylinder, around for the full skip of twenty-four teeth and in Fig. 22 15 the members have moved half their distance and are still turning.

Fig. 23 shows hook member up, and as soon as it began to rise it was swung away from lever 88 because index pawl lever has 20 been pushed away from lever 63. The friction and strain of the parts kept hook 90^a in contact with end 88'' of lever 88 until the strain was relieved by the beginning of the elevation of member 74. The crank-arm is 25 still at rest, or cut-out, and will remain so until the end 88' of lever 88 is dropped away from abutting arm 86 to give locking bolt 80 a chance to revolve and connect the parts together again. The contacting of the 30 pawl-lever with trigger 115 swung pawl 120 into working position but lug G' of slide 123 was already down past the end of the pawl.

In Fig. 24 the index pawl has dropped 35 back one tooth only, being arrested by the first index pin back from zero position; the trigger 115 is still in contact with the end 113 of pawl lever 37 so weighted pawl 120 remains in operative position and slide 123 is about to rise. Hook member 74 is just 40 starting down once more and now is in contact with trigger lever 98. On Fig. 25 it has pulled the trigger 98 down and thus freed dead-stop lever 88 from the spring retaining catch 94 so that the end 88'' has 45 risen while the end 88' has fallen away from abutting arm 86 and allowed the locking bolt 80 to revolve as soon as one of the recesses 81' in hub 81 came in line with it 50 and therefore bolt 80 once more locks crank arm 75 to the revolving shaft 52 and in Fig. 25 the crank arm is just ready to start up and move the color car toward the yarn cylinder. The movement of lever 88 caused the 55 rise of pawl 138 and its engagement with a tooth of the three toothed ratchet 141 which it turned one sixth of a revolution and, because the ratchet is fast on shaft 142 the shaft and cam 143 and ratchet 157 also 60 turned. The movement of cam 143 caused one of its lobes to move roller 144 out of the cam depression onto the top of a lobe so that the end 149 of lever 146 was raised drawing 65 with it flexible connector 150 and the weighted end 119 of pawl 120 so that the working

tip of the pawl is moved out of its operative position and the scraper is "cut-out."

It is necessary to thus cut-out the scraper because the former movement of the index-pawl up to zero resulted in no color stripe 70 and now Fig. 25 shows that this pawl 120 would be set by lever 115 for a scrape if it was not stopped by the scraper cut-out. Fig. 26 shows that pawl 156 has drawn half away toward the right and is revolving 75 its ratchet 157 because it was enabled to reach a tooth by reason of the movement of ratchet 141 by pawl 138, with the result that roller 144 is being dropped into a recess of cam 143 and end 149 of lever 146 is 80 shown as partly down and weighted pawl partly swung to the left. Fig. 27 shows lever 146 as wholly moved into its normal position. The color-box has moved forward one-sixth of the crank's revolution and is 85 just to contact with the yarn cylinder. These Figs. 21 to 26 therefore show both the scraper cut-out, or the sixth condition, and also the manner of making skips of over twenty-four teeth which calls for the 90 color-car cut-out on a large skip.

I will now by Figs. 27 and 28 illustrate graphically the action of the color-car cut-out when operated by the spring index pin 35. From zero in Fig. 26 the pawl-lever 95 was retracted to the spring pin 35 shown in Fig. 27 as anywhere in the upper half of the circle and consequently the roller 103 carried by lever 105, which is pivoted on and carried by the index lever comes opposite 100 recess 102 in the circular rim 101 as it must always do, and being impelled into the recess by the spring 107 the consequent movement of the end 108 against the curved end 109 of lever 71 swings hook member 74 over 105 so that hook 90^a contacts against lever 88, just as it did in Fig. 21 when moved by lever 63, and the downward urge of hook member 74 again throws lever 88 into operative position to cause abutting arm 86 to 110 contact with the end 88' and cause locking bolt 80 to be revolved and once more free crank-arm 75 from revolving shaft 52.

Condition three calls for a color stripe 115 when spring pin 35 reaches the zero position and it must be plain that if the isolated, jacquard-indicated pin 111 had been protruded into the mouth of recess 102 in Fig. 27, as shown in Fig. 10, then roller 103 could not have entered the recess and therefore the hook member 74 would not have been swung over against end 88'' of lever 88 and the color-car motion would not have been cut-out; therefore when the pusher urged the index pawl lever to the XX position the color-car would have proceeded to make a stripe on the yarn on the cylinder as indicated by the jacquard protruded pin 111. Whenever the spring pin reaches zero 120 it always stops there, for the index pawl 125

lever invariably is arrested by it, and when it reaches zero the jacquard operates and sets up the index pins for a new arrangement according to the design.

5 Whereas I have shown and illustrated one good embodiment of my invention, I do not limit myself to that one form but instead am entitled to claims of the broadest nature, susceptible of the most liberal interpretation, 10 for I believe myself to be the first successful and therefore the pioneer inventor in this class of mechanism.

What I claim and desire to secure by Letters Patent is:

15 1. In a device as described, in combination, a warp-holder, means for printing a definite color upon the warp at variable intervals of its length, and pattern controlled mechanism having a working and an idle 20 stroke for actuating said means.

2. In a device as described, in combination, means for supporting a warp-unit, means for printing stripes on said warp-unit at spaced-apart longitudinal points 25 thereof, pawl mechanism for controlling said means, and check-controlled means controlling the operation of said mechanism.

3. In a device of the class described, the combination of a yarn support, means for 30 stretching the yarn on said support, color impression mechanism, and automatic means for variably positioning the yarn support and color impression mechanism for the impression of color on the stretched yarn.

35 4. In a device as described, in combination, means for supporting a single warp-unit, color-applying mechanism engaging said warp-unit step by step, pawl mechanism determining the intervals of operation 40 of said color-applying mechanism and check-controlled mechanism for selectively and automatically actuating the last-named means.

45 5. In a device as described, in combination, means for supporting a single warp-unit, color-applying mechanism intermittently engaging said warp-unit *seriatim*, oscillatable means for actuating said mechanism, and check-controlled means for selectively determining the intervals of operation 50 of said mechanism.

55 6. In a device of the class described, the combination of a drum, means for stretching yarn upon the drum, color impression mechanism, and pattern controlled means for relatively positioning the drum and color impression mechanism for the application of color impressions to the stretched yarn.

60 7. In a device as described, in combination, a movable warp support, means for advancing said warp support step by step successively, an actuator therefor, selectively controlled mechanism determining a definite cycle of movements for said actuator

enabling said warp support to move variable distances, color-applying mechanism engageable with said warp at a definite point, and means acting in time with said selectively-controlled mechanism for actuating said color-applying mechanism. 65

8. In a device as described, in combination, a movable warp support, means operable to move said warp support periodically, said means capable of moving said warp support over variable distances, color applying 70 mechanism engageable with the warp support at a definite position, and check-controlled mechanism for automatically actuating said means and said mechanism.

9. In a device as described, in combination, a movable warp support, color-applying mechanism engaging said warp support periodically, means for periodically actuating said warp support to move it over variable distances, and check-controlled means 85 for synchronizing the operation of said movable warp support and said color-applying mechanism.

10. In a device as described, in combination, a movable warp-support, means for 90 periodically moving said warp-support in one direction, means movable in one direction only and effective to vary the distances traversed by said warp-support periodically, color-applying mechanism adapted 95 to engage said warp-support, check-controlled mechanism controlling the operating of said second-named means, and means movable in a direction opposite to the second-named means and effective to stop 100 the operation of said color-applying mechanism.

11. In a device as described, in combination, a movable warp-support adapted to be moved step by step over variable distances apart, mechanism determining a maximum distance of movement for said warp support, means for actuating said mechanism by a single stroke at a time, said means moving said warp-support over still greater 110 distances by a plural stroke, and color-applying mechanism engageable with said warp-support and actuated in time with said aforementioned actuating means. 105

12. In a device as described, in combination, 115 color-printing mechanism, a movable warp-support engaged by said mechanism and adapted to be moved periodically over variable distances, selective mechanism determining a definite number of distances over 120 which said warp-support is to be moved, an actuator for said warp-support acting thereon by successive strokes, each stroke of said actuator effecting the movement of said warp-support, and being controlled by said 125 selective mechanism.

13. In a device as described in combination, a movable yarn holder, means adapted

to wind yarn onto said holder, and jacquard mechanism adapted to move said holder independently of said means.

14. In a device as described, in combination, a movable warp-support, means for automatically feeding said warp support step by step, color applying mechanism automatically engaging with said warp-support, brake mechanism for retarding the movement of said warp-support, a ratchet mechanism adapted to actuate said first-named means, and means controlled by said ratchet mechanism for actuating said color-applying mechanism.

15. 15. In a device as described, in combination, a movable warp-support, means for periodically feeding said warp-support along, an intermittently-operated member moving from inactive position to active position to actuate said means, color-applying mechanism controlled by said member and engageable with said warp-support at certain intervals, means for stopping said color-applying mechanism from operating, and means for actuating said stopping means when said member resumes inactive position.

16. In a device of the class described, in combination, a movable warp-holder, color-applying mechanism adapted to engage said warp-holder, ratchet mechanism adapted to turn various parts of a revolution, a pawl adapted to engage said ratchet mechanism to turn it, means whereby the movements of said ratchet mechanism are imparted to said movable warp-holder, and check-controlled means for selectively actuating said color-applying mechanism.

17. In a device as described, in combination, a movable warp-holder, means adapted periodically to impart color stripes to warp upon said warp-holder, a member operable to move said warp-holder over varying distances, selective mechanism effective to move said member step by step or by a multiplicity of steps, said mechanism imparting to said member a varying stroke, and means adapted to stop the operation of said first-named means after said mechanism has made its largest stroke.

18. In a device as described, in combination, a movable warp-holder, mechanism for actuating said warp-holder intermittently, means for printing color stripes against said warp holder periodically, a rotatable member determining the periods of operation of said means, an actuator for said rotatable member adapted to be checked at various positions in one direction and making its operative stroke in a counter-direction.

19. In a device as described, in combination, a yarn carrier, means for color striping the yarn upon said carrier and making consecutive and non-consecutive color stripes thereon, the consecutive stripes applied by

said means blending thus producing color ridges, means for removing said color ridges, schedule controlled means for controlling the engagement of said carrier and color striping means, and means rendered self-acting by the last-named means for actuating said ridge removing means.

20. In a device as described, in combination, a yarn-carrying holder, means for printing color impressions upon yarn carried by the holder, yarn engaging scraper mechanism, schedule controlled means for periodically starting said scraper mechanism, and means controlled by the last-named means for automatically stopping the operation of said scraper mechanism.

21. In a device as described, in combination, a movable warp-holder, means for advancing said warp-holder periodically a determinate number of steps, said warp-holder moving equal distances for equal steps, and check-controlled means for automatically combining several of said steps so as to increase the distances traversed by said warp-holder.

22. In a device as described, in combination, a warp-holder movable over graduated distances, color-applying mechanism adapted to engage said warp-holder after each of its moves, and a common pattern controlled mechanism for registering said warp-holder and said color-applying mechanism.

23. In a device as described, in combination, a warp-holder movable over graduated distances, color-applying mechanism adapted to engage said warp-holder periodically, uniformly stroking mechanism, means whereby said stroking mechanism is adapted to act as a common controller for starting and stopping said warp-holder and said color-applying mechanism, and schedule controlled mechanism for rendering said stroking mechanism self-acting.

24. In a device as described, in combination, a warp-holder movable successively over graduated distances, color-applying mechanism adapted to engage said warp-holder periodically, scraper mechanism associated with said color-applying mechanism, uniformly-stroking mechanism serving as a common controller for said warp-holder and said color-applying mechanism, and means controlled by said last-named mechanism for actuating said scraper mechanism.

25. In a device as described, in combination, a warp-holder, a color mechanism striping the same, a uniformly stroking member, schedule controlled means for varying the duration of stroke of said member periodically, and means controlled by said member for causing said warp holder to move over graduated distances in a self-acting manner.

26. In a device as described, in combination, an index wheel, a drum adapted to hold

- a warp, jacquard controlled means for causing said index wheel to move over graduated distances, means controlled by said index wheel for moving said drum periodically, 5 and color - applying mechanism acting in time with said last-named means.
27. In a device as described, in combination, an index wheel, means for stopping said index wheel at every move, an actuator 10 for said index wheel and acting by uniform strokes, check controlled mechanism adapted to alter the duration of said strokes and warp printing mechanism operated by said index wheel.
- 15 28. In a device as described, in combination, a warp-carrying drum, periodically operating color-applying mechanism, a periodically - operating actuator designed to move said drum periodically, a scraper device carried by said color-applying mechanism, and means timed by said actuator for operating said scraper device.
29. In a device as described, in combination, a warp carrying member, mechanism 25 moving into and out of position to apply a color stripe upon said warp, a continuously moving member, means controlled by said member for actuating said mechanism, and check-controlled mechanism controlling the 30 last-named means.
30. In a device as described, in combination, a periodically rotated drum, check-controlled rotatable means providing stop positions for said drum, and color-applying 35 mechanism acting upon said drum during its stop positions and controlled by said rotatable means.
31. In a device as described, in combination, a rotatable drum, an index wheel having 40 checks defining stop positions for said drum, color-applying mechanism operable to engage said drum during its stop positions, means governed by said checks for actuating said drum, a check isolated from the other 45 checks, and means governed by the last-named check for rendering said mechanism inoperative.
32. In a device as described, in combination, a rotatable drum, a continuously rotatable shaft, drum actuating mechanism, a movable check carried by said mechanism, color mechanism coöperating with said drum, means carried by said shaft for actuating said mechanism, and means operable 55 upon movement of said check to render said color mechanism inoperative.
33. In a device as described, in combination, a movable yarn support, a printing device operable to make color impressions on 60 the yarn of said support periodically, and jacquard means operable for moving said support intermediate said printing periods whereby said support comes to rest at equal intervals of time.
- 65 34. In a device as described, in combina- tion, color-printing mechanism, a rotatable warp-holder engaged by said mechanism, actuating means for said mechanism, a scraper attachment carried by said mechanism, and an actuator for said scraper attachment, said 70 actuating means and said actuator adapted to interengage, and pattern means for controlling said actuator.
35. In a device as described, in combination, color-printing mechanism, a rotatable 75 warp holder, an actuator for said holder movable over consecutive distances, and mechanism adapted to selectively cause said actuator to cover longer distances than each consecutive distance.
36. In a device as described, in combination, color-printing mechanism, a movable warp-holder, an actuator for said holder movable over consecutive distances, mechanism adapted to selectively cause said actuator to cover longer distances than each consecutive distance, scraper mechanism associated with said color-printing mechanism, and means controlled by said actuator for setting said scraper mechanism in motion 80 during the second of two consecutive movements of said actuator.
37. In a device as described, in combination, a warp-holder, color-printing mechanism, scraper mechanism associated with 85 said color-printing mechanism, a treadle for actuating said scraper mechanism, schedule controlled means for operating said color-printing mechanism, and means rendered self-acting by said last-named means for actuating said treadle.
38. In a device as described, in combination, a rotatable member, a series of checks arranged in a consecutive series, an actuator for said rotatable member having an operative sweep extending over a certain number of said checks only, means for selectively releasing any of said checks to interrupt said actuator, color-printing mechanism, a rotatable warp holder engaged by said mechanism, and means actuated by said rotatable member and adapted to operate said color-printing mechanism.
39. In a device as described, in combination, a rotatable member, an actuating arm 105 adapted to actuate said member, a friction device resisting each turn of said member, means for graduating the distance of travel of said actuating arm, color-printing mechanism, a movable warp-holder engaged by 110 said mechanism, and means coöperating with said rotatable member for timing the actuation of said color-printing mechanism when said member moves over prescribed distances, and stopping it when moving over 115 other distances.
40. In a device as described, in combination, a ratchet wheel, a pawl making forward strokes to selectively engage different teeth of said wheel, each stroke cutting 120
- 130

- in one or more teeth up to a maximum less than the total number of teeth, so as to move said wheel over varying distances, a continuously operating actuator for said 5 pawl, a movable warp-holder, color-printing mechanism engaging said warp holder, and means for transmitting the motion of said wheel to said color-printing mechanism automatically.
- 10 41. In a device as described, in combination, a ratchet wheel, said wheel carrying checks arranged in a circle, means for actuating a check at any point of said circle of checks and causing it to project out of 15 said wheel, a pawl capable of making a forward stroke against said ratchet wheel between two fixed points in a definite arc of said checks, the projection of any check retarding the reverse movement of said 20 pawl, means for automatically reversing said pawl, means for releasably stopping said pawl at one of the mentioned points during its forward movement, said pawl upon the projection of a check beyond the 25 other mentioned point making its full stroke and another partial stroke governed by said check, a movable warp-holder, printing mechanism engaging said warp-holder, means for transmitting the movement of 30 said wheel to said color-printing mechanism, and means operable automatically in time with the projection of said check last referred to and adapted to stop said color-printing mechanism.
- 35 42. In a device as described, in combination, a yarn carrying drum, a color car reciprocating thereunder and applying color to the yarn at each stroke, means for turning said drum when the color car is out of 40 contact therewith, means acting in time with said last-named means for stopping the drum when the car is in contact therewith, scraper mechanism accompanying said color car and adapted to engage the drum periodically, 45 means for actuating said scraper mechanism, and predetermining means controlling said color-car and rendering said last-named means self-acting.
43. In a device as described, in combination, a movable warp-holder, color-printing mechanism engageable therewith, scraper mechanism, a check-controlled timer for both mechanisms, and means governed by 50 said timer for automatically controlling the 55 intervals of operation of said mechanisms.
44. In a device as described, in combination, a movable warp holder, color-printing mechanism engaging said holder, scraping mechanism, a controller member, a series of 60 checks governing varied-length strokes for said controller member, means responding to the strokes of said member for operating said printing mechanism, means acting in time with said last named means for actuating 65 said scraper mechanism, means for automatically positioning any of said checks, and automatic means for stopping the operation of said printing mechanism.
45. In a device as described, in combination, a movable yarn carrier, color-applying mechanism coöperating therewith, a continuously rotating shaft, means controlled by 70 said shaft for actuating said mechanism, scraper mechanism accompanying said color-applying mechanism, and means controlled 75 by said shaft for automatically actuating said scraper mechanism.
46. In a device as described, in combination, a yarn carrying drum, color-applying mechanism coöperating therewith, a continuously rotating shaft, means controlled by 80 said shaft for actuating said mechanism, scraper mechanism coöperating with said color-applying mechanism, means controlled by said shaft for moving said drum, and 85 means controlled by said shaft for actuating said scraper mechanism.
47. In a device as described, in combination, a primary mover, color-applying mechanism, a yarn carrying drum engaged by 90 said mechanism, means controlled by said primary mover for moving said drum over equal distances, a distance increasing controller for said drum and means for selectively actuating said controller in time with 95 said primary mover.
48. In a device as described, in combination, a continuously rotating shaft, a yarn carrying drum movable over equal distances, means for actuating said drum to cause 100 it to move over increasing distances, color-printing mechanism controlled by said shaft and adapted to act on said yarn, and means controlled by said shaft for timing the intervals of operation of said actuating means. 105
49. In a device as described, in combination, color-printing mechanism, scraper mechanism accompanying the same, a rotatable yarn carrying drum, automatically operated means adapted to cause said printing mechanism to engage said drum, means for operating the scraper mechanism, and an oscillating member controlling said drum and scraper operating means. 110
50. In a device as described, in combination, color-printing mechanism, a yarn carrying drum, motion transmitting mechanism, a drum actuator disposed at one side of said motion-transmitting mechanism and controlled by it, scraper means coöperating 115 with said color-printing mechanism and disposed at the other side of said motion mechanism and jacquard controlled means whereby said scraper means is controlled by said motion-transmitting mechanism. 120
51. In a device as described, in combination, a yarn-carrying drum, color-printing mechanism adapted to move into engagement therewith, mechanism for actuating said color-printing mechanism, scraper 125

- means coöperating with said printing mechanism, and an oscillatable member controlling the stopping of said printing mechanism and the stopping of said scraper means.
- 5 52. In a device as described, in combination, yarn engaging color-applying mechanism, scraper means coöperating with said color-applying mechanism, mechanism for continuously operating said color-applying mechanism, means controlled by said mechanism adapted to periodically operate said scraper means, a cut-out for said color-applying mechanism, and a cut-out for said scraper means.
- 10 53. In a device as described, in combination a yarn carrying drum, means for advancing said drum over similar distances, a distance-increasing controller for said drum, scraper mechanism coöperating with said drum, means actuated by said first named means for operating said scraper mechanism, and other means for cutting out said scraper and acting in time with said distance-increasing controller.
- 15 54. In a device as described, in combination, a yarn carrying drum, a color-car having provision for applying color stripes to yarn upon said drum, means for actuating said drum, scraper means associated with said color-car, a member movable to one position for cutting out said color car, means controlled by said member when moving to another position for controlling said scraper means, and means for moving said member to either position.
- 20 55. In a device as described, in combination, a yarn carrying drum, color-applying mechanism adapted to engage said drum to lay a color-stripe thereupon, means for rendering said mechanism inoperative, a rotating member adapted to actuate said drum, a trip located at the point of completion of the stroke of said rotating member, means whereby said trip when actuated may operate said first named means, and means carried by said member adapted to operate said trip.
- 25 56. In a device as described, in combination, a yarn carrying drum, color-applying mechanism engageable with said drum periodically to stripe it transversely, a scraper attachment associated with said mechanism, said mechanism traveling from a point in advance of to a point beyond either side of said drum, means for continuously operating said mechanism, means for periodically moving said drum by larger or smaller skips determining consecutive equal distances or irregular distances, means controlled by said last-named means for stopping said drum as said mechanism applies a color stripe thereagainst, and means for actuating said scraper attachment when said drum turns consecutive equal distances.
- 30 57. In a device as described, in combination, color-stripe laying mechanism, a rotatable yarn carrying drum movable over distances equal severally to the width of said color stripes, means for moving said drum consecutively over equal distances, selectively controlled means adapted to allow said drum to move non-consecutively, scraper mechanism movable with said stripe laying mechanism, means holding said scraper mechanism inactive during the non-consecutive striping of the drum, and means for automatically actuating said scraper mechanism during consecutive turns of said drum over equal distances.
- 35 58. In a device as described, in combination, a yarn carrying drum, an actuator for moving said drum a specific distance at each stroke, color-printing means, means automatically and selectively stopping said printing means during certain strokes of said actuator while out of engagement with said drum, and means timed by said selectively acting means for actuating said printing mechanism to engage said drum.
- 40 59. In a device as described, in combination, a yarn carrying member, color-printing mechanism adapted to lay color-stripes upon said yarn, means for successively positioning said member to allow said color-printing mechanism to apply two blending stripes against the yarn, selective means coöperating with said last-named means for positioning said member successively at isolated positions for allowing the printing of spaced apart yarn stripes, a scraper, and means for automatically applying said scraper against said member when said first-named means is in operation.
- 45 60. In a device as described, in combination, a yarn carrying member, a rotatable stroking actuator for advancing said member during its forward stroke only, means for giving said actuator partial back strokes so as to vary its forward strokes and cause said member to move over variable distances, a continuously operative pusher effecting the forward strokes of said actuator, means whereby the variable forward stroke of said actuator will move said member variable distances, color applying mechanism engaging said member during the back strokes of said actuator, and means engageable with said actuator at the end of its full back stroke for cutting out said color-applying mechanism.
- 50 61. In a device as described, in combination, a yarn carrying member, a rotating member adapted to advance said yarn member, color-applying mechanism engaging said yarn and operated independently of said rotating member but controlled by said member for stopping purposes, an oscillatable actuator for said rotating member, and means engaging said actuator for controlling the stopping of said mechanism.

62. In a device as described, in combination, a yarn carrying member, ratchet means for moving it periodically, by single or plural tooth skips, a swinging actuator for said means, color-applying mechanism engageable with said member at each move, and operated independently of said means, a scraper, a treadle for operating said scraper when depressed, means moving toward said treadle to operate it, and controlled in time with said color-applying mechanism, a coupling movable between said treadle and last-named means, and intercepting the latter to receive a stroke for depressing said treadle, and means for actuating said coupling, said actuator engaging said last-named means once during every move of said ratchet means and ineffectively operating it, and operable during the turning of said ratchet means another tooth to effectively operate said coupling. 65
63. In a device as described, in combination, a warp support, color-printing mechanism adapted to engage said support, means for, altering the relative position of said support and said mechanism to definite positions, and pattern controlled mechanism for predeterminedly altering said relative positions intermediate said definite positions. 70
64. In a device as described, in combination, a warp carrier, means for operating said carrier periodically, color-printing mechanism engaging said carrier and operated independently of said means, and schedule controlled mechanism timing the intervals of engagement of said printing mechanism and said carrier. 75
65. In a device as described, in combination, a movable yarn holder, color-printing mechanism adapted to lay color impressions thereupon, mechanism adapted to actuate said holder, an index device having a series of movably interchangeable parts co-operating with said last-named mechanism to graduate the moves of said holder, and jacquard controlled means for periodically setting up said movably interchangeable parts. 80
66. In a device as described, in combination, a yarn carrier, color-printing mechanism engageable therewith, an index device, a schedule controlled series of checks carried by said index device successively set-up in interchangeable relation to locate the various points of engagement of said holder and said printing mechanism, and means controlled by said index device for bringing said carrier and said printing mechanism into the mentioned various points of engagement. 85
67. In a device of the class described, the combination of a yarn holder, color-stripe applying means, and automatic means for effecting a variable relative advance and positive control of said relative advance of said holder and stripe applying means for the application of color-stripes. 90
68. In a device as described, in combination, a rotatable index wheel, said wheel being set so as to turn less than one revolution, means for resetting said index wheel to move it beyond its maximum turning, jacquard controlled mechanism for automatically setting said index wheel and actuating said resetting means, a yarn holder controlled by said index, and color-printing mechanism engaging said holder. 95
69. In a device as described, in combination, a variable movable warp-holder, color-printing mechanism engageable therewith and capable of making single moves against corresponding single moves of said holder, a movable device, means controlled by said device for moving said holder, means for actuating said device move by move, and schedule controlled means modifying said actuating means periodically to cause said device to make plural moves against single moves of said color-printing mechanism. 100
70. In a device as described, in combination, a yarn holder, coloring mechanism engageable therewith to apply impressions in consecutive and non-consecutive order, the consecutive impressions blending and producing color-ridges, a color ridge removing device, schedule controlled automatic mechanism, means actuated by said mechanism for operating said coloring mechanism, and means for causing said color ridge removing device to act contemporaneously with said coloring mechanism. 105
71. In a device as described, in combination, a yarn holder, color-printing mechanism applying color impressions against said yarn, certain of which blend, thus producing color ridges, a color ridge remover engageable with said yarn holder, a movable index device timing the action of said ridge remover and mechanism acting in accordance with a predetermined schedule for automatically selecting the moves of said index device. 110
72. In a device as described, in combination, a yarn holder, means for operatively color-stripping said yarn automatically, and a jacquard-controlled index wheel set and reset automatically so as to actuate said means. 115
73. In a device as described, in combination, a yarn holder, color-stripe applying mechanism engaging therewith, means for operatively effecting contact between said yarn holder and mechanism periodically in a manner to leave a color-stripe upon said yarn, and an index wheel controlling the stripe-applying function of said mechanism. 120
74. In a device as described, in combination, a yarn holder, color-stripping means engageable therewith, actuating means therefor, a driving pawl urging said actuating means, a scraper associated with said mecha- 125

nism, and means controlled by said driving pawl adapted to actuate said scraper.

75. In a device as described, in combination, a yarn holder, color stripe laying mechanism engageable therewith, an actuator therefor, a pawl intermittently urging said actuator, a scraper movable with said mechanism, and means engaged by said pawl during the inactivity of said actuator for actuating said scraper.

76. In a device as described, in combination, a yarn holder, a color stripe laying device engaging said holder and capable of producing consecutive stripes thereupon, an actuator for said device, a pawl engageable intermittently with said actuator to urge the same, said consecutive color stripes producing color ridges, and means coöperating with said pawl while the latter is in engagement with said actuator for actuating said ridge remover.

77. In a device as described, in combination, means for applying color impressions, a yarn holder engaged periodically by said means, certain of the color impressions made by said means upon said holder blending and thus producing color ridges, a color ridge remover, a member adapted to move in counter directions, means actuated by said member during the latter's movement in one direction for starting and stopping said color applying means, and schedule controlled means for controlling said member, said member adapted to actuate said color ridge remover during its movement in a counter direction.

78. In a printing drum, in combination, a yarn holder, a color-car having means for applying color impressions upon said yarn consecutively, some of said applied color impressions blending and producing color ridges, means timed to automatically remove color ridges, and schedule controlled means for operating said color-car for striping action.

79. In a device as described, in combination, a drum having a determinate number of teeth, means engaging said teeth for revolving said drum, a color car adapted to engage said drum, a series of jacquard controlled pins less in number than the teeth on said drum, and automatically operating means for operating with said pins for the purpose of controlling the last-named means whereby said drum may be turned the distance of a plurality of its teeth.

80. In a device as described, in combination, a warp-holder making successive turns, a coloring device traversing said warp holder transversely and having an initial and a final point of movement beyond either side of the warp holder, means for moving said warp holder while said coloring device is out of contact with said warp holder, means for automatically moving said coloring device, mechanism acting in accordance with a definite schedule for determining the

points of contact between said holder and said coloring device, and means rendered self-acting by said last-named mechanism for operating the holder independently of the coloring device.

81. In a device as described, in combination, a warp holder, means for laying color stripes upon the warp thereon, certain of said stripes being applied consecutively and producing color ridges, means for removing color-ridges between consecutive color stripes, means for automatically timing the actuation of said last-named means, and check-controlled mechanism controlling the engagement of said warp-holder with said stripe-laying means.

82. In a device as described, in combination, a yarn support, a movable color mechanism, means for contacting said holder and said mechanism at variably spaced apart distances, and means for moving said color mechanism over equal distances.

83. In a device as described, in combination, a movable yarn carrier, an actuator therefor adapted to move said carrier over variable distances, an index carrying a series of interchangeably movable elements engaged by said actuator and providing consecutive variable moves therefor, color printing mechanism, and means controlled by said elements for timing the operation of said printing mechanism.

84. In a device as described, in combination, a yarn holder, coloring mechanism adapted to engage said yarn holder, means for successively engaging said yarn holder with said coloring mechanism to produce stripes on the yarn, means for predeterminedly controlling the color-printing mechanism, and means actuated by said last named means for interrupting the order of successive engagement between said holder and said coloring mechanism in order to produce separate stripes in the yarn.

85. In a device as described, in combination, a warp holder, having a warp supporting surface color applying means, for applying color impressions to the warp while supported on said surface, means for bringing said warp-holder and said color-applying means into a step by step engagement one with the other, pattern controlled mechanism, and means controlled by said pattern mechanism for graduating the steps of engagement between said holder and said color-applying means.

86. In a device as described, in combination, a member adapted to support yarn, color-impression mechanism adapted to engage said yarn, an automatic actuator adapted to arrange contact between said yarn and said mechanism during each cycle of its motion, and pattern controlled means for varying the distance between similar color impressions during successive cycles.

87. In a device as described, in combination, a yarn carrier, color-printing mechanism adapted to engage said carrier at certain points of contact, an index device, means controlled by said index device for stepping down the movement of said carrier in unison therewith, and jacquard controlled means for coöperating with said index device for variably separating the points of contact between said carrier and said printing mechanism. 70
88. In a device as described, in combination, a yarn carrier, a color laying mechanism, a jacquard controlled predetermined device, means operating with and independently of said predetermined device for causing said color mechanism to lay color impressions upon said carrier, and means also controlled and rendered self-acting by 80
- 20 said device for selectively changing the relative position of said carrier and said color-laying mechanism periodically.
89. In a device as described, in combination, a member adapted to support yarn, color-impression mechanism adapted to engage said yarn, an actuator adapted to effect engagement between said yarn and said mechanism, and jacquard controlled means for predetermined variable distances between similar color impressions during successive units of time. 90
90. In a device as described, in combination, yarn engaging color-applying mechanism, a schedule-controlled means for operating said color-applying mechanism, a yarn engaging scraper, means controlled by said color-applying mechanism adapted to periodically operate said yarn engaging scraper, and a cut-out for said scraper rendered self-acting by said schedule controlled means. 95
91. In a device as described, in combination, a rotatable device carrying an annular series of projectable pins, means for selectively projecting said pins, an actuator for said device adapted to be interrupted by a fixed arcuate number of said projected pins, said device when actuated, capable of replacing said fixed arcuate number of pins by another arcuate series, color mechanism acting in time with said device, and a warp holder engaged by said mechanism and operated by said device. 100
92. In a device as described, in combination, a warp holder, a schedule controlled regulator therefor making the holder move equal or unequal skips, means for applying color to said holder, a scraper timed by said regulator to operate periodically, means for operatively positioning said scraper, a coupling adapted to prevent the action of the last-named means and means also controlled by said regulator and controlling said coupling. 110
- 65 93. In a device as described, in combination, a ratchet wheel, a lever concentric therewith and carrying a pawl, releasable checks arranged at various points on said wheel interrupting the movement of said pawl thereagainst, means for moving said pawl from any of said checks up to a definite position, color printing mechanism, a movable warp-holder engaged by said color mechanism, and means controlled by said ratchet wheel for transmitting motion to 75 said color printing mechanism. 120
94. In a device as described, in combination, a yarn carrier, color printing mechanism adapted to make color impressions on said carrier, an actuator adapted normally to actuate said mechanism successively, and jacquard mechanism operable to interrupt the normal successive actuation of said printing mechanism. 130
95. In a device as described, in combination, a warp holder, color applying mechanism engageable therewith, a normally inoperative scraper, schedule controlled mechanism, a regulator actuated by said last-named mechanism to cause said color applying mechanism to engage said holder, and an actuator for said scraper causing it to operate only while contiguous stripes are being laid. 135
96. In a device as described, in combination, a yarn carrier having a determinate number of stripe receiving positions, a jacquard controlled index device containing movable elements less in number than the number of said positions, means whereby said elements may successively determine stripe receiving positions according to a schedule, color mechanism adapted to stripe said carrier and an actuator for said mechanism controlled by said elements. 140
97. In a device as described, in combination, a warp holder adapted to receive a determinate number of color impressions, color mechanism adapted to operatively engage said warp holder, a jacquard controlled index device determining the points of engagement between said warp holder and said color mechanism during successive equal intervals of time and means rendered self-acting for eliminating the surplus color produced by the blending of contiguous color impressions. 145
98. In a device as described, in combination, a member adapted to hold yarn, means for operatively printing spots of color on said yarn automatically during equal intervals of time, and a pattern controlled device for determining the distance between spots printed during successive intervals of time. 150
99. In a device as described, in combination, a warp holder having color impression positions at spaced-apart distances, a jacquard controlled index device having movable elements spaced apart at greater distances than said first-named distance, color 155

- mechanism adapted to operatively engage said warp and means operated by said device for predeterminately causing engagement between said warp holder and said color mechanism at said color impression positions. 5 for operatively and predeterminately causing said support and said mechanism to contact according to a schedule, and means rendered self-acting for distributing color between contiguous color impressions. 70
100. In a device as described, in combination, a drum having color receiving positions at uniformly spaced apart angular intervals, a jacquard controlled index device having movable elements uniformly spaced apart at greater angular intervals, color applying mechanism adapted to operatively engage said drum and means operated by said device for predeterminately causing engagement between said drum and said color-applying mechanism at said color-receiving positions. 10 107. In a device as described, in combination, a movable yarn carrier, a color mechanism adapted to operatively contact said carrier and jacquard controlled mechanism predeterminately actuating the moves of 75 said carrier.
108. In a device as described, the combination of a drum for supporting yarn, color-stripe applying mechanism, and automatic means for variably positioning the drum and 80 color stripe applying mechanism for the application of color-stripes.
109. In a device of the class described, the combination of a drum for supporting yarn, a color-stripe applying mechanism, and pattern controlled means for positioning the drum and color-stripe applying mechanism for the application of color-stripes. 85
110. In a device of the class described, the combination of a drum for supporting 90 yarn, a color-stripe applying mechanism, and means acting automatically for variably actuating the drum and color-stripe applying mechanism alternately for the application of color-stripes at intervals. 95
111. In a device as described, the combination of a drum for supporting coils of yarn, a color-stripe applying mechanism for applying color-stripes to the yarn at intervals, and pattern-controlled means for rotating the drum and operating the stripe-applying mechanism alternately. 100
112. In a machine for color-striping yarn, the combination of a drum for supporting the yarn, pattern controlled means for rotating the drum different amounts determined by the pattern, color-stripe applying mechanism, and automatic means for operating the color-stripe applying mechanism to apply color-stripes to the yarn on the 110 drum. 105
113. In combination, mechanism adapted to form yarn into bights, and automatic means for applying color stripes across said bights at variable intervals. 115
114. In combination, a yarn holder, mechanism for winding the yarn into coils upon the holder, and pattern controlled means for applying color stripes across said coils. 120
115. In a device of the character described, in combination, a yarn carrier, color applying means, and jacquard controlled means for moving the carrier to present different sections to the color applying means 125 and for moving the color applying means for the application of color.
116. In a device of the class described, the combination of a drum for supporting bights of yarn, a color-stripe applying 130
105. In a device as described, in combination, a cylinder adapted to support yarn, means for rotating said cylinder in a step by step manner, color applying mechanism adapted to engage said cylinder to apply color impressions thereto, an actuator causing contact between said cylinder and said mechanism and a jacquard controlled device for predetermining the distance between said contacts. 55
106. In a device as described, in combination, a yarn support, color mechanism, means

means for applying color-stripes to the yarn on the drum, and automatic means for rotating the drum variable amounts to present a section of the yarn to the color-stripe applying mechanism while the latter is functionally inoperative.

117. In a device of the class described, the combination of a drum for supporting bights of yarn, a color-stripe applying means for applying color-stripes to the yarn on the drum, and pattern controlled means for rotating the drum to present a section of the yarn to the color-stripe applying mechanism while the latter is functionally inoperative, and for operating the color-stripe applying mechanism when the drum is at rest.

118. In a machine of the class described, the combination of a yarn holder for holding yarn for the application of color, color applying means for applying color to the yarn on the holder, and pattern controlled means for moving the yarn holder for the application of color to the yarn at intervals.

119. In a machine of the class described, the combination of a yarn holder for holding yarn for the application of color, color applying means for applying color to the yarn on the holder, and pattern controlled means for moving the holder variable distances and for actuating the color applying means for applying color to the yarn on the holder.

120. In a machine of the class described, the combination of a yarn holder for supporting a yarn arranged thereon in coils, a color-stripe applying mechanism for applying a color-stripe transversely of the coils of yarn that the yarn shall have the desired color at a plural number of equal intervals throughout its length, and pattern controlled means for relatively positioning the yarn holder and color-stripe applying mechanism.

121. In a machine of the class described, the combination of a drum for supporting a yarn coiled thereon, a color-stripe applying mechanism for applying a color-stripe transversely of the coils of yarn, and pattern means for controlling the relative position of the drum and color-stripe applying mechanism for the application of a color-stripe to the coils of yarn.

122. In a device as described, in combination, a yarn holder, means adapted to wind yarn onto said holder, printing mechanism adapted to make color stripes across said holder whereby each stripe will color-print said yarn at equally spaced apart distances throughout its length, and jacquard mechanism operable to alter the relative position of said holder and said printing mechanism.

123. In a device as described, in combination, means adapted to support a warp arranged in coils, color-impression mechanism

adapted to stripe the warp on the supporting means, means adapted to cause contact between the warp on the supporting means and said mechanism whereby a color stripe will make one impression on each of said 70 coils of yarn, and jacquard mechanism adapted to control the actuation of said stripping mechanism and the location of said stripes on said yarn.

124. In a machine of the class described, the combination of a yarn holder, a color impression mechanism constructed and arranged to apply color on the yarn for the formation of single tufts, and automatic means for variably positioning the yarn 80 holder and color impression mechanism for successive impressions.

125. In a machine of the class described, the combination of a drum for holding yarn, a color impression means constructed and 85 arranged to apply color to the yarn of a width for the formation of a single tuft, and pattern controlled means for relatively positioning the drum and color impression applying means.

126. In a machine of the class described, the combination of a yarn holder, a color-stripe applying mechanism for applying a color-stripe to the yarn on the holder, and pattern controlled means for alternately 95 moving the holder and color-stripe applying mechanism and for cutting out one of the stripe applying movements of the color-stripping means to effect a double movement of the yarn holder.

127. In a machine of the class described, the combination of a warp support, a color-stripe applying mechanism for applying a color-stripe to the warp on the support, means for automatically effecting a plurality of movements of the warp support to 105 present the warp to color applying position and for operating the color-stripe applying mechanism at the completion of said plural movements of the warp support.

128. In a machine of the class described, in combination, a warp support, color mechanism for applying color stripes to the warp upon the support, means for automatically moving the support to color receiving position and for operating the color applying means, and means for automatically cutting out the operation of the color applying means.

129. In a device as described, in combination, a yarn carrier, a printing mechanism adapted to make color-impressions on said carrier, an actuator adapted to cause contact periodically between said carrier and said mechanism, an actuator adapted to 125 change variably the relative position of said carrier and said mechanism, and means acting in time to check the movement changing said relative position at equal intervals of time.

130. In a machine of the class described, in combination, a yarn-drum, an angularly movable member for rotating said drum step-by-step, a connection between said member and drum to move the latter proportionately to the movement of the former but through a smaller angle, pattern controlled means for operating the angularly movable member, and means for applying a color stripe to the yarn. 65
131. In a machine of the class described, in combination, a warp-drum for supporting warp, means for applying color stripes upon the warp at variable intervals, an index wheel for angularly positioning said drum and having a step-down connection with the drum, and pattern controlled mechanism for rotating the index wheel through variable angles. 70
132. In a machine of the class described, in combination, a warp-holder, means for applying color stripes upon the warp at variable intervals, mechanism having a working and an idle stroke for moving the warp-holder relatively to the color applying means, and pattern mechanism for controlling the length of said stroke. 75
133. In a machine of the class described, the combination of a warp-drum, an index wheel for rotating the drum through variable angles, stops upon the index wheel for controlling the movement of the wheel, pattern controlled means for selectively operating said stops, a master stop for periodically bringing the index wheel to a predetermined position relative to the pattern controlled means, and color-stripe applying means for applying color stripes to the warp. 80
134. In a device of the class described, the combination of a yarn holder, a color-stripping mechanism for applying stripes to the yarn on the holder, a scraper, and means for automatically moving the scraper to or from its operative position. 85
135. In a device of the class described, the combination of a yarn holder, a color stripping mechanism for applying stripes to the yarn on the holder, a scraper, and pattern controlled means for automatically moving the scraper to or from its operative position. 90
136. In a device as described, in combination, a warp holder, color-applying mechanism engageable therewith, a scraper adapted to engage the warp on said holder, jacquard controlled mechanism, a regulator actuated by said jacquard controlled mechanism to cause said color-applying mechanism predeterminedly to engage said holder, and an actuator for said scraper causing it to operate only while identical and contiguous color impressions are being laid. 95
137. In a machine of the class described, the combination of a yarn holder having a yarn supporting surface, color-stripe applying means operable to press the yarn against said surface while applying a stripe to the yarn, and means for automatically moving the yarn holder to variously spaced color receiving positions. 100
138. In a device as described, in combination, a yarn holder, color printing mechanism, a pattern device operable to effect the relative positioning of said holder and said mechanism, and a retarding means to act in unison with said pattern device. 105
139. In a device of the class described, the combination of means for holding under tension yarn arranged in bights, and automatic means for printing said yarn at variously spaced apart intervals. 110
140. In a machine of the class described, the combination of means to support a warp arranged in bights, a color impression means constructed and arranged to apply color to the bights of yarn of a width for the formation of a single tuft, and means for variably positioning the support and color impression applying means. 115
141. In a device as described, in combination a yarn support, color-impression mechanism adapted to engage the yarn on said support, an actuator acting in cycles, means for causing said actuator to effect contact between said yarn and said mechanism during any cycle, means for varying the distance between identical color impressions made during successive cycles, and jacquard mechanism controlling said first and said second named means. 120
142. In a device of the class described, in combination, a yarn support, means for forming yarn into bights on said support, means for automatically color-printing the yarn at irregular distances, and means for automatically eliminating color ridges between contiguous color-prints. 125
143. In combination, automatic means operable to move yarn variable distances and a color mechanism operable to contact the yarn. 130
144. In combination, mechanism adapted to form yarn into bights and automatic means for applying color to the bights at variable distances. 135
145. In a device as described, in combination, a yarn support, a color mechanism operable to contact the yarn, means operable to move variable distances and a step down device associated with said means to alter the relative position of said color mechanism and said yarn. 140
146. In a machine of the class described, the combination of a yarn holder, a color impression mechanism constructed and arranged to apply color on yarn for the formation of a color spot less than the length 145

of two tufts, and automatic means for variably positioning the yarn holder and color impression mechanism for successive impressions.

- 5 147. In a machine of the class described, the combination of a drum, a color impression mechanism constructed and arranged to impress color upon yarn carried by the drum, and pattern controlled means for im-
10 parting to the drum rotative step move-
ments to position the yarn for the applica-
tion of color spots of less length than that required for two tufts.

148. In a device of the class described, the

combination of a yarn support, a color- 15
striping mechanism for applying stripes to
the yarn supported by said support, a color-
ridge remover, and means associated with
said mechanism for automatically actuating
said ridge remover. 20

In witness whereof I have hereunto set
my hand and affixed my seal this eighteenth
day of August 1919.
